Primary Examiner — Marianne Pandozzi*Assistant Examiner* — Jae Liang(74) *Attorney, Agent, or Firm* — Epstein Drangel LLP; Robert L. Epstein(57) **CLAIM**

The ornamental design for a drinking cup with lid, as shown and described.

DESCRIPTION

FIG. 1 is a perspective view of a drinking cup with lid showing our new design;

FIG. 2 is a front elevational view thereof;

FIG. 3 is a rear elevational view thereof;

FIG. 4 is a left side elevational view thereof;

FIG. 5 is a right side, elevational view thereof;

FIG. 6 is a top plan view thereof; and,

FIG. 7 is a bottom plan view thereof.

The broken lines in the drawings depict portions of the drinking cup with lid that form no part of the claimed design.

1 Claim, 4 Drawing Sheets(56)
